UNITED STATES PATENT OFFICE.

LOUIS STEINBERGER, OF BROOKLYN, NEW YORK.

INSULATING COLLECTOR-SPOOL.

1,382,609.

Specification of Letters Patent. Patented June 21, 1921.

Application filed March 6, 1920. Serial No. 363,692.

To all whom it may concern:

Be it known that I, LOUIS STEINBERGER, a citizen of the United States, and a resident of the borough of Brooklyn, county of 5 Kings, city and State of New York, have invented certain new and useful Improvements in Insulating Collector-Spools, of which the following is a specification.

My invention relates generally to improvements in insulating devices of the spool type which are to be used in combination with co-acting brushes in automobile installation, or the like.

One of the objects of the invention is to 15 provide an insulator of the type disclosed so constructed that the hub or central portion will readily be kept clean and free from dirt, dust and foreign material, the presence of which has a deleterious effect.

20 Other objects will appear from the following description and claims.

Referring to the drawings:

Figure 1 is a vertical section of a form of spool embodying my invention.

25 Fig. 2 is a sectional view on line 2—2 of Fig. 1.

Fig. 3 is a detail of the metallic ring surrounding the "bobbin" portion of the insulating spool.

30 In the drawings like reference characters refer to like parts:

10 is the body or "bobbin" portion and 11 and 12 are the flanges extending circumferentially and radially from each side of 35 the body portion. In the form illustrated both surfaces of each flange are smooth and so constructed and formed that the thickest portion is adjacent the hub and each flange decreases in thickness to its periphery, as 40 well understood in the art.

Embedded in the outer surface of the body "bobbin" portion is a metal ring or insert 20 which extends entirely around the central body portion of the spool, as shown.

45 The metal ring is provided with two flanges 21 and 22 and with a central raised portion 23 having a cylindrical surface 24 and two vertical sides 25 and 26, which intersect at right angles with the surfaces 27 and 28 of

50 the flanges 21 and 22, thereby forming grooves 30 and 31 between the raised metal portion 23 and the sides of the insulating flanges 11 and 12, the said grooves thus having metallic surfaces at the bottom thereof,

by reason of which the grooves are readily 55 kept clean. When the spool is in operation the action of centrifugal force will tend to keep the grooves 30 and 31 free and clean of dirt, dust, oil and any other deleterious matter, and these grooves by reason of their 60 metallic linings or surfaces can be more easily and readily cleaned than otherwise, because of the impervious, strong and non-absorbent quality of metal which renders the same capable of ready and thorough 65 cleansing. In the operation of the structure the brushes grind off because of the continual revolution of the collector and the carbon, powder, dust and oil, which has been drawn into the grooves, is more readily 70 thrown off the spool and the surface of the metal against which the brush acts, is always clean. This structure is efficient because it is well known that these spools 75 revolve in use and it is very desirable that the dust, carbon and all material of like nature if permitted to form and stick to the structure, renders it much less effective.

While I have shown a spool having but two flanges and a single metal insert it is 80 obvious that the spool may be extended in size so it may be provided with a plurality of insulating flanges and a plurality of metal ring inserts when such an enlarged construction is desired.

85 A hole 40 extending axially through the spool is provided as shown for the mounting of the spool in place and it may or may not be lined with metal 50 as desired.

The insulating portions of my device may 90 be made of any approved insulating material, but I prefer to use in this construction a moldable insulating material well known in the art as "electrose."

95 It is to be understood that the above description and drawings are merely illustrative and the invention is not to be limited in any respect, except as defined in the subjoined claims.

Having thus described my invention what 100 I claim as new and desire to secure by Letters Patent is:

1. A spool insulator provided with circumferential radially extending insulating flanges, and a metal ring secured to the central portion of the spool and extending along thereof between the flanges, said ring provided with a centrally arranged raised por-

- tion forming grooves with metallic bottom surfaces between the central metallic raised portion and insulating flanges.
2. A spool insulator, provided with circumferential radially extending insulating flanges, a metal ring molded to the central portion of the spool and extending along thereof between the flanges, said ring provided with a centrally arranged raised portion forming grooves with metallic bottom surfaces between the central metallic raised portion and the insulating flanges.
3. A spool insulator provided with circumferential radially extending insulating flanges, a metal ring secured to the central portion of the spool and extending along thereof between the flanges, said ring provided with a centrally arranged raised portion having a cylindrical surface and vertical sides, said metallic raised portion and said insulating flanges forming grooves therebetween, the grooves having metallic bottom surfaces extending between the central metallic raised portion and the insulating flanges.
4. A spool insulator provided with a central portion of insulating material, and with circumferential radially extending flanges on either side thereof, a metal ring secured to the central portion and extending between the flanges, the said ring having a centrally arranged raised portion provided with a cylindrical top surface and vertical side surfaces, forming grooves between the said raised metal portion and the insulating flanges, the grooves being metal lined on the bottom and on a side thereof.

Signed at the borough of Manhattan, city, county and State of New York, this 1st day of March, 1920.

LOUIS STEINBERGER.

In presence of—
ISABEL R. FLETCHER.
